UNITED STATES PATENT OFFICE.

WILLIAM A. MILLS AND JOHN T. FISKE, OF PORT CHESTER, NEW YORK.

GAS-RANGE.

SPECIFICATION forming part of Letters Patent No. 768,390, dated August 23, 1904.

Application filed December 11, 1903. Serial No. 184,748. (No model.)

To all whom it may concern:

Be it known that we, WILLIAM A. MILLS and JOHN T. FISKE, citizens of the United States, residing at Port Chester, in the county of 5 Westchester and State of New York, have invented an Improvement in Gas-Ranges, of which the following is a specification.

Our invention relates to means for obtaining access to the burners of a gas-range below the oven-bottom and between the same and the broiling-chamber with which gas-ranges are usually provided for the twofold purpose of lighting and visually inspecting the burners. Heretofore access has been provided to these burners, but the space was exceedingly limited and the visible area restricted.

In carrying out our invention the entire oven-bottom is movable and we provide means 20 for raising the same bodily or at the forward part, for holding the oven-bottom when raised, and for returning the same to an initial position, which means preferably comprise a rod placed transversely of the gas-range, means 25 connected thereto and extending to contact with the oven-bottom, and a handle thereon outside of the range. In raising the oven-bottom bodily the same may be lifted entirely clear of and above its supports or it may be 30 in part supported at the back edge and be raised entirely at the forward edge. To prevent the oven-bottom moving forward while being raised at the forward edge, we provide means adjacent to the edge having the least 35 motion for holding the same in position, and which means preferably comprise end notches in the side supporting-flanges and pins depending from the corners of the oven-bottom.

In the drawings, Figures 1 and 2 are vertical cross-sections through a gas-range and at right angles to one another and showing the preferred form of our invention, the upper portions of said range being broken through and Fig. 3 is a sectional plan of the gas-range 45 directly above the oven-bottom. Fig. 4 is a cross-section illustrating a form of our invention. Figs. 5 and 6 are vertical cross-sections at right angles to one another, showing a form of our invention; and Figs. 7 and 8 are vertical cross-sections at right angles to one an-

other, showing still another form of our invention.

In the preferred form of our invention, *a* represents the front of the range, *b* the back, *c* the top, *e* the sides, *d* the bottom of the 55 range, and *2* the feet by which the range is preferably supported on a suitable foundation.

f represents the oven-bottom; *h*, burner-tubes beneath the oven-bottom and in the upper portion of the underneat or broiling chamber usually employed in gas-ranges.

a' *a''* are doors hinged to the front and respectively closing the oven and the broiling-chamber.

We provide support-flanges *3*, secured to the respective sides *e* of the gas-range and coming directly beneath the oven-bottom for supporting the same. These flanges at their back ends are provided with notches *4*, and at the 70 adjacent corners of the oven-bottom *g* are depending pins *5*, which pass into these notches *4* to prevent the oven-bottom being accidentally drawn forward.

We provide a shaft *i*, passing transversely 75 across and through the sides of the gas-range slightly below the oven-bottom and forward of the central line of the gas-range, upon the outer end of which shaft *i* outside of the gas-range is a handle *k* for turning the same. Upon this shaft within the range and in the upper part of the broiling-chamber, beneath the oven bottom, approximately in the center, is a cam *l*. The office of this cam is to raise the entire forward portion of the oven-bottom into the inclined and dotted position 80 shown in Fig. 1. This cam is made of such a size that the elevation of the forward edge of the oven-bottom will be about two inches in a gas-stove of usual dimensions, the forward 85 end of the oven-bottom being raised up to approximately the under edges of the brackets *6*, forming rack-supports and which in series are secured to the sides *e* of the gas-range. When the oven-bottom is thus elevated, access 90 is obtained to the burners for lighting the same and for visual inspection, after which the handle and shaft are turned and the cam lowered, the oven-bottom descending to its initial position with the return movement.

In the form of our invention shown in Fig. 4 the lifting device comprises an arm 7 and handle 8 in the general form of a bell-crank and located at about the central portion of a gas-stove upon a shaft and in about the position of the cam 7. (Shown in Figs. 1 and 2.) This arm 7 extends beneath the oven-bottom and the handle 8 through an opening in the plate between the oven-door and the door of the broiling-chamber, and by swinging said parts into the position shown in dotted lines the oven-bottom is raised entirely at the forward part and supported upon the arm 7, which in this position is substantially vertical. The oven-bottom is lowered by simply reversing the position of the parts.

In the form of invention shown in Fig. 5 and the left-hand side of Fig. 6 the back b' , sides c' , and bottom d' of the gas-range are made double—that is, with outer and inner walls. The shaft i' extends across through the sides and between the walls of the double bottom near the forward edge. Upon this shaft is a handle k' outside the gas-range and crank-arms 11 within. On the under side of the oven-bottom are lugs 9, and links 10 extend from the same to the free ends of the crank-arms 11, the bottom of the broiling-chamber or inner portion of the double bottom being slotted for the movement of the crank-arms 11. In this form of the invention when the shaft i' is turned by the handle the crank-arms and the links are straightened and the entire forward portion of the oven-bottom raised. There is but a slight difference between the form at the right hand of Fig. 6 and the form at the left hand. In the form at the right hand the movement of the crank-arm 11 on the shaft i' and the movement of the link 10 are in the double side walls and the upper end of the link 10 is bent forward and passes through a slot in the side wall in the oven proper and connects with a lug rising from the oven-bottom at the forward corner. The operation, however, is identical.

In the form of invention shown in Figs. 7 and 8 the back b'' , sides c'' , and bottom d'' of the gas-range are double—that is, with inner and outer walls, the same as shown in Figs. 5 and 6. In this form of our invention there are two shafts i'' and i''' , which extend across between the outer side walls and through between the walls of the double bottom, one end of the shaft i'' projecting and having a handle k'' , Fig. 8. These two shafts are connected by one or more sets of crank-arms $n n'$ and links 14. Upon these shafts i'' and i''' are crank-arms $m m'$ in pairs, and links 13 extend from the free ends of said crank-arms to lugs 9 and 12 on the under side of the oven-bottom, near the four corners thereof.

When the handle k'' is operated, the shafts i'' and i''' are simultaneously moved by virtue of their connection by the crank-arms $n n'$

and connecting-rods 14, also simultaneously moving the sets of crank-arms $m m'$, the links 13, and raising the oven-bottom bodily into the horizontal dotted position, Fig. 7. In this position the crank-arms $m m'$ and the links 13 bear a substantially straight-line relation to one another. The reverse movement lowers the oven-bottom to and upon its support-flanges 3.

We prefer the form of invention shown in Figs. 1 to 3, inclusive, or the form shown in Fig. 4 to the forms shown in Figs. 5 to 8, inclusive, because there are less parts to make, to assemble, to arrange in the gas-stove, and to get out of order or replace.

In our improvement the integrity of the oven-bottom is maintained—that is to say, it is not provided with an aperture and with raised flanges for a sliding structure through which access is obtained to the burners and which interferes with the full and complete use of the oven-bottom. Our improvement is simpler, it is less expensive to construct, and there are no complications of parts to get out of order and require adjustment.

We claim as our invention—

1. In a gas-range and in combination, a separate movable oven-bottom, supports therefor, burners beneath the oven-bottom, and means for raising the oven-bottom bodily to obtain access to the burners.

2. In a gas-range, and in combination, a separate movable oven-bottom, supports therefor, burners beneath the oven-bottom, means for raising the oven-bottom bodily to obtain access to the burners, and means for preventing any forward sliding movement of the oven-bottom while being raised.

3. In a gas-range and in combination, a separate and detachable oven-bottom, supports therefor along the sides of the range, a shaft passing across through the sides of the range near the front edge of the oven-bottom, a cam structure connected to the shaft and means for turning the shaft to raise the forward portion of the oven-bottom by the cam so as to provide an opening beneath the forward edge for the full width of the oven-bottom providing access to the burners and for the visual inspection thereof.

4. In a gas-range and in combination, a separate and detachable oven-bottom, supporting-flanges along the respective sides of the gas-range upon which the oven-bottom rests, said flanges at their back ends being notched, pins secured to the adjacent corners of the oven-bottom and received in said notches and thereby fixing the relation of the back edge of the oven-bottom to its supports, and means for raising the oven-bottom along its forward and opposite edge for providing access to the burners.

5. In a gas-range and in combination, a separate and detachable oven-bottom, supporting-flanges along the respective sides of the

gas-range upon which the oven-bottom rests, said flanges at their back ends being notched, pins secured to the adjacent corners of the oven-bottom and received in said notches and thereby fixing the relation of the back edge of the oven-bottom to its supports, a shaft passing across and through the sides of the gas-range and near the front, a handle outside of the range for turning the shaft, a cam on the shaft inside of the range and about centrally beneath the oven-bottom and adapted when turned to raise the forward portion of the oven-bottom so as to provide access to the burners and a visual inspection of the same.

6. In a gas-range and in combination, a separate movable oven-bottom, supports therefor, burners beneath the oven-bottom, and means for raising the entire forward portion of the oven-bottom to obtain access to the burners.

7. In a gas-range, and in combination, a separate movable oven-bottom, supports therefor, burners beneath the oven-bottom, means for raising the entire forward portion of the

oven-bottom to obtain access to the burners, 25 and means for preventing any forward sliding movement of the oven-bottom while being raised.

8. In a gas-range and in combination, a separate and detachable oven-bottom, supports 30 therefor along the sides of the range, a shaft passing across through the sides of the range near the front portion thereof, means for turning the said shaft, means actuated by the shaft and connected to the oven-bottom and interposed between the two, by the movement of which the oven-bottom is raised bodily and an opening provided beneath the forward edge for the full width of the oven-bottom to give 35 access to the burners and for the visual inspection thereof.

Signed by us this 8th day of December, 1903.

WILLIAM A. MILLS.

JOHN T. FISKE.
